UNITED STATES PATENT OFFICE.

HORACE L. RIDGERS, OF GRANUM, ALBERTA, CANADA.

SKATE.

Application filed February 17, 1927, Serial No. 168,993, and in Canada February 15, 1927.

The invention relates to improvements in skates and an object of the invention is to provide a skate having a sectional blade which permits of the heel or toe ends of the skate being raised from the ice, thereby facilitating the act of skating due to the free movement of the foot so occasioned and further to arrange the structure such that the raised portions have a normal tendency to return to the ice.

A further object of the invention is to construct the skate so that there is a cushioning structure interposed between the blade and the foot.

15 A further object of the invention is to construct the skate in a simple, durable and comparatively inexpensive manner and such that the blade sections can be locked against yielding when it is desired to use the skate for a special purpose such as hockey playing.

With the above more important objects in view, the invention consists essentially in the arrangement and construction of parts hereinafter more particularly described, reference being had to the accompanying drawing, in which:—

Fig. 1 is a side view of the skate as it appears attached to a boot.

Fig. 2 is a side view of the skate with the 30 heel section in the raised position.

Fig. 3 is a vertical sectional view longitudinally and centrally through the skate with the blade thereof shown in side elevation.

Fig. 4 is a horizontal sectional view at 35 4—4' Figure 1 and looking in the direction of the applied arrow.

Fig. 5 is an enlarged detailed horizontal sectional view at 5—5' Figure 1.

Fig. 6 is a perspective view of the locking 40 pin.

In the drawing like characters of reference indicate corresponding parts in the several figures.

The front and rear plates 1 and 2 of the 45 skate are attached to the sole 3 and heel 4 of the boot 5 in the usual manner and are herein shown as secured by the screws 6. The heel plate is provided centrally with a downwardly extending socket 7 of predetermined 50 length and the front plate 1 is also provided with a forward downwardly extending socket 8 and a rearwardly located socket 9, these latter being aligned with the former socket and being positioned so that they centrally 55 underlie the foot.

Each socket is provided with a pair of

opposing vertical guide slots 10 and in the slots I locate slidably cross pins 11, 12 and 13 which are carried by upstanding posts 14, 15 and 16, the posts being slidably received 60 within the sockets and having their lower ends forked and permanently riveted as indicated at 17, 18 and 19 to the skate blade. Cushioning springs 20 are interposed between the upper ends of the posts and the plates, 65 the springs normally pressing the pins to the lower ends of the slots. Obviously these springs yieldingly support the weight of the body on the skate and accordingly act as cushioning members between the blade 70 and the boot.

The blade is formed from a front or toe section 21 and a rear or heel section 22 and when the sections are both in their horizontal or normal positions as shown in Figure 1, the 75 front end of the heel section butts the rear end of the toe section. To the forward end of the heel section, I permanently secure by rivets 23 an inverted substantially U-shaped extension 24 and the forward end of the extension receives the rear end of the front blade section and is connected thereto by a rivet 25 which passes slidably through a lengthwise extending slot 26 formed in the rear end of the skate section 21. The forward end of the extension is cut to provide an end notch 27 and a hook 28 and according to the above arrangement, the blade sections can have varying relative positions ranging from the flat position shown in Figure 1 to 80 the fully up swung position shown in Figure 2, it being understood that the rivet 25 slides in the slot 26 during the movement.

The post 9 is supplied with a split ring 29 which has the ends thereof terminating in 95 hooks 30 and a coiled spring 31 is provided, the spring having the ends thereof caught in the hooks 28 and 30. The spring is designed to normally pull the hook 28 ahead with the result that the rear section of the blade normally remains in the position shown in Figures 1 and 3. If it is desired to lock the sections of the blade in the latter position, this is done by passing a locking pin 32 through side openings 33 provided in the extension 24 and positioned such that when the rear blade section is in the flat lying position, the pin 32 when passed through the openings 33 and slot 26 will take a position in the rear end of the slot as shown best in Figure 3. 100 The holes 33 are of the well known key hole 105 shape and the pin 32 is supplied with a tip 34

adapted to lock the pin upon rotation after it has been passed through the registering holes in the slot.

I provide the plate 1 also with a downwardly extending lug 35 and this receives slidably a comparatively short rod 36, the forward end of which is screw threaded to receive a nut 37 and a washer 38. A coiled spring 39 is mounted on the rod between the washer 38 and the lug and the rear end of the rod terminates in forked arms 40 and 41 which span the post 9 and have their rear ends carrying a cross pin 42. A hinged bar 43 is also provided, the forward end of the said bar being pivotally mounted on the pin 42 and the rear end of the bar being hingedly connected as indicated at 44 to the heel plate. By tightening up the nut 37, one can tension the spring 39 and this will cause a continuous forward pull on the heel plate through the arms and hinged bar.

This spring and connections associated therewith co-operate with the spring 31 to bring the skate sections into their normally flat lying position and the hinged bar acts as a support for the foot when the same is in the raised position as shown in Figure 2 where it will be observed that the hinged bar is held forcibly in contact with the under part of the boot sole.

It will be seen from the above description that this skate allows the foot very free movement which is not possible with the stiff or non-sectional blade customarily used.

35 What I claim as my invention is:—

1. A skate comprising a front attaching plate, a rear attaching plate, a front blade section, means connecting the front blade section to the front plate, a rear blade section, 40 means connecting the rear blade section to the rear plate, an extension permanently attached to the forward end of the rear blade section, means slidably connecting the forward end of the extension to the rear end 45 of the front blade section and a spring connecting the extension to the support of the front blade section.

2. A skate comprising a front attaching plate, a rear attaching plate, a front blade section, means connecting the front blade section to the front plate, a rear blade section, means connecting the rear blade section to the rear plate, an extension permanently attached to the forward end of the 50 rear blade section, means slidably connecting the forward end of the extension to the

rear end of the front blade section, a spring connecting the extension to the support of the front blade section and means for releasably locking the extension to the front 60 blade section.

3. A skate comprising front and rear attaching plates, a pair of sockets extending downwardly from the front plate and a single socket extending downwardly from the rear plate, a forward blade section and a rearward blade section, a pair of posts permanently secured to the forward blade section and slidably entering the sockets of the front plate, a post permanently secured to the rear blade section and slidably entering the socket of the rear plate, coiled springs mounted within the sockets and engaging the upper ends of the posts, means preventing withdrawal of the posts from the sockets, a bar 70 permanently secured to the rear blade section and having the front end thereof straddling the rear end of the front blade section, a pin slidably connecting the latter end of the arm to the latter end of the front blade 80 section and a coiled spring interposed between one of the posts of the front plate and the bar.

4. A skate comprising front and rear attaching plates, a pair of sockets extending 85 downwardly from the front plate and a single socket extending downwardly from the rear plate, a forward blade section and a rearward blade section, a pair of posts permanently secured to the forward blade section 90 and slidably entering the sockets of the front plate, a post permanently secured to the rear blade section and slidably entering the socket of the rear plate, coiled springs mounted within the sockets and engaging the upper 95 ends of the posts, means preventing withdrawal of the posts from the sockets, a bar permanently secured to the rear blade section and having the front end thereof straddling the rear end of the front blade section, a pin slidably connecting the latter end of the arm to the latter end of the front blade 100 section, a coiled spring interposed between one of the posts of the front plate and the bar and an adjustably spring pressed hinged 105 bar having the rear end thereof attached to the rear attaching plate and the front end to the forward attaching plate.

Signed at Granum, this 18th day of December, 1926.

HORACE L. RIDGERS.
